CLAIM

The ornamental design of a spinning fishing reel, as shown and described.

DESCRIPTION

FIG. 1 is a rear, bottom and side perspective view of a spinning fishing reel, showing our new design;

FIG. 2 is an elevational view from one side thereof;
FIG. 3 is an elevational view from a side opposite that in FIG. 2;

FIG. 4 is a top plan view thereof;

FIG. 5 is a bottom plan view thereof;

FIG. 6 is a front elevational view thereof; and

FIG. 7 is a rear elevational view thereof.

FIG. I

FIG. 2

FIG. 3

FIG. 4

FIG. 5
